UNITED STATES PATENT OFFICE.

HARRY ESTEROW, OF NEW YORK, N. Y.

DESIGN FOR A CIGAR LIGHTER.

Application filed May 12, 1927. Serial No. 21,950. Term of patent 14 years.

To all whom it may concern:

Be it known that I, HARRY ESTEROW, a citizen of the United States, and a resident of the city, county, and State of New York, have invented a new, original, and ornamental Design for Cigar Lighters, of which the following is a specification.

Reference is to be had to the accompanying drawing, forming a part hereof, in which—

I claim:

The ornamental design for a cigar lighter, as shown.

HARRY ESTEROW.
